OVERLOAD CIRCUIT BREAKER

Clarence W. Kuhn, Wauwatosa, Wis., assignor to
Cutler-Hammer, Inc., Milwaukee, Wis., a corpora-
tion of Delaware

Application October 27, 1943, Serial No. 507,215

7 Claims. (Cl. 200—124)

This invention relates to improvements in overload circuit breakers of the thermal type.

More particularly the invention relates to such circuit breakers using the so-called solder type element which commonly comprises a ratchet wheel anchored by a eutectic solder to a fixed part, the solder melting under given thermal conditions to release the ratchet wheel for rotation.

An object of the invention is to provide such a circuit breaker which will function reliably upon the occurrence of short-circuits as well as upon lesser overloads.

Another object is to provide a thermal element of the type aforementioned which will be responsive to relatively small but prolonged overloads and which will be protected against impairment of its tripping function by a short-circuit.

Another object is to provide a circuit breaker of the character aforesaid which will be free tripping and which may be produced in very simple form at relatively low cost.

Various other objects and advantages of the invention will hereinafter appear.

As will be understood, attainment of the aforesaid objects involves radical departures from the present designs of solder type thermal elements which are commonly provided with and dependent for action upon, heater coils or heated cores subject to burn-out upon the occurrence of short-circuits. According to the present invention it is proposed to so construct the thermal element as to enable use of a high resistance core member for the solder ring, which core member is insulated from the solder but yet is in a closely coupled thermal relation therewith and which core member is throughout its extent capable of carrying a very heavy current, being protected throughout its extent against dangerous hot spots.

One embodiment of the invention is more or less schematically shown in the accompanying drawing; it being understood that the embodiment illustrated is susceptible of various modifications without departing from the scope of the appended claims.

In the drawing,

Figure 1 is a view of the thermal element alone, certain parts thereof being shown in section.

Fig. 2 is a schematic view of a free tripping circuit breaker utilizing the thermal element of Fig. 1, and

Fig. 3 is a schematic view showing the circuit connections of the thermal element and of the contacts of the device of Fig. 2.

Referring to Fig. 1, the same shows a thermal element comprising a ratchet wheel 5 supported

on a core 6 in turn non-rotatably supported by terminals 7 and 8. The ratchet wheel 5 is fixed to a metal sleeve 9 which surrounds the core 6 in a suitably spaced relation to accommodate a thin film 10 of eutectic solder and certain coverings for the core member 6, which core is formed of any suitable high resistance material to effect melting of the solder film when said core is subjected to a flow of current exceeding under certain conditions a predetermined value. The core 6 neglecting the coverings thereof is as shown of uniform diameter throughout its length, said core being optionally extended into the terminals with a press fit or being welded, soldered or otherwise attached to surfaces of the terminals.

The portion of the core 6 between terminals 7 and 8 is throughout its extent provided with a thin insulating covering 11 which as will be understood must be integral or intimately bonded with the core for close thermal coupling of the core and solder film. In practice this insulating coating may be produced in different ways and with different materials. Good results have been obtained by using Lohm, Advance and Nichrome cores and forming thereon a thin coating 11 of the order of .001 inch of nickel oxide; such insulating coating in turn having formed thereon a thin coating 12 of the order of .001 inch of copper or silver to which the solder film will bond. However, it is to be understood that the present invention is not limited to such specific constructions.

In practice the ratchet wheel sleeve 9, the solder film 10 and coating 12 all preferably extend into close proximity to the terminals 7 and 8, all being separated therefrom by insulating washers 13. As previously pointed out, the core has uniformity throughout its length and in the construction shown there is similar uniformity of the surrounding parts, this minimizing chance of excessive heating of any cross section of the thermal element under any overload conditions.

With such a construction the solder film and core have a close thermal coupling, while at the same time the solder film is electrically insulated from the core and with such a construction it has been found that the thermal element will function as desired either upon occurrence of a moderate overload for a prolonged period or upon occurrence of short-circuit in contrast to the previously known constructions. The close thermal coupling of the solder film and the core results in melting of the solder instantly in the event of short-circuit.

Referring to Fig. 2, the circuit breaker scheme

matically shown therein comprises two pivoted contact arms 15 and 16 pivoted at points 17 and 18, respectively, these arms carrying respectively cooperating contacts 19 and 20. The line 21 indicates the walls of an arcing chamber into which the contacts 19 and 20 project, said walls constituting an up limit for contact arm 15 and a down limit for contact arm 16. The contact arm 16 is normally held in the full line position shown, by a pawl 16^a engaging a ratchet wheel 5 of a thermal element such as shown in Fig. 1. On the other hand, the contact arm 16 is biased by a spring 22 to move the contact 20 downwardly when the solder locking the ratchet wheel 5 melts to release said ratchet wheel for rotation. The contact arm 15 is movable at will through the medium of an operating lever 23 carrying at its lower end a spring pressed plunger 24 engaging the upper surface of the contact arm and movable to the left or right of the pivot point 17 of said arm to bias contact 19 for movement into or out of engagement selectively with contact 20. The spring 25 biasing the plunger 24 is shown in dotted lines. As illustrated the operating lever 23 is in on position, throwing the plunger 24 to the left of the pivot point 17 of the arm 15, thereby biasing contact 19 into engagement with contact 20 which is shown as locked in its up position.

Assuming melting of the solder locking the ratchet wheel 5 said ratchet wheel is rendered free to rotate and spring 22 rocks the contact arm 16 to move contact 20 to its dotted line position out of engagement with contact 19, the latter contact being restrained by a suitable stop 26 from following the contact 20 in downward direction. Thus tripping of the circuit breaker is free from influence by the operating lever 23 which remains in on position until manually moved to off position. The contact arm 16 when tripped moves counterclockwise under the bias of spring 22, thus bringing into close proximity to the lower end of operating lever 23 the extremity of an extension 27 provided on arm 16 at its rear end.

When the operating lever 23 is moved to off position following tripping of the contact arm 16 it effects a dual function. It reverses the bias on contact arm 15 to throw contact 19 into the dotted line position out of range of the contact 20 and furthermore engages the extension 27 of contact arm 16 and through the medium thereof resets said contact arm 16 in its normal, full line, position. Thus following movement of the operating lever 23 to off position and assuming hardening of the solder to lock ratchet wheel 5 the circuit breaker is in condition to be reclosed manually at will by a simple movement of the operating lever to on position to return contact arm 15 to its full line position, whereupon if an overload persists the contact arm 16 again trips, free from interference by holding of the operating lever in on position.

Referring now to Fig. 3, the same shows in cross section the contact arms 15 and 16 and shows in outline a thermal element like that of Fig. 1 together with electrical connections for said contact arms, and said thermal element. More specifically the thermal element has its terminal 7 electrically connected to a circuit terminal 30 and has its terminal 8 connected through a flexible conductor 31 to contact arm 16. The contact arm 15 in turn is connected through a flexible conductor 32 to a second circuit terminal 33. Thus assuming the terminals to be connected respectively to the wires of a circuit L1, L2 current flows from line L1 to and through the high resistance

core of the thermal element to contact arm 16 and with contacts 19 and 20 in engagement, then flows to contact arm 15 and thence to line L2. The thermal element is thus made responsive to the electrical condition of the circuit controlled by the circuit breaker, the ratchet wheel and the conducting parts surrounding the core being external to the circuit.

As previously pointed out, the construction of the thermal element causes the solder film to melt instantly upon short circuit. Thus with the breaker construction of Fig. 2 the contact 20 is instantly released to interrupt the circuit L1, L2 including core member 6. The breaker thus trips so quickly as to prevent damage thereto by short circuit and in tripping affords the desired protection of the circuit L1, L2.

What I claim as new and desire to secure by Letters Patent is:

1. The combination with a circuit controlling device having a part to be restrained, said device effecting quick interruption of circuit upon release of said part, of restraining means for said part of said device, comprising a solder type thermal element connected in part in the circuit controlled by said device to be responsive to overloads by melting of its solder, said thermal element comprising means which under overload from short-circuit insures melting of the solder without burn-out of said element, and said element and said device being progressively responsive to effect interruption of the controlled circuit within a period protecting the current carrying parts of said thermal element against burn-out by overload resulting from short-circuit.

2. The combination with a circuit controlling device having a part to be restrained and having manual operating means through the medium of which it may be moved to make or break circuit while said part is restrained, said device upon release of said part affording quick interruption of circuit free from interference by said manual operating means, of restraining means for said part of said device, comprising a solder type thermal element connected in part in the circuit controlled by said device to be responsive to overloads by melting of its solder, said thermal element comprising means which under overload from short-circuit insures melting of the solder without burn-out of said element, and said element and said device being progressively responsive to effect interruption of the controlled circuit within a period protecting the current carrying parts of said thermal element against burn-out by overload resulting from short-circuit.

3. A thermal restraining device for electric switches and other devices, comprising a fixed member, a relatively movable member and a thin film of solder to lock said relatively movable member to said fixed member subject to release upon melting of said solder, such restraining device having a conducting path for current to heat and melt said solder film as a function of a relatively small overload in current persisting for a given period of time and to melt said solder film substantially instantaneously as a function of a heavy overload current, said current conducting path having uniformity of conductivity from terminal to terminal and having surroundings minimizing danger of hot spots therein.

4. A thermal restraining device for electric switches and other devices, comprising relatively rotatable members, one of annular form and the other constituting a non-rotatable support for the former, and means comprising a solder film

to lock said annular member to said supporting member subject to release upon melting of said solder film, such restraining device having a current conducting path axially through said annular member for heating said solder film and melting the same under given current conditions, said conducting path having uniformity of conductivity from terminal to terminal and having surroundings minimizing danger of hot spots therein in the event of maximum overload.

5. A thermal restraining device for electric switches and other devices, comprising a high resistance core member having from terminal to terminal a thin surrounding covering intimately bonded thereto, affording insulation thereof and also affording a surface to which solder will bond, a sleeve surrounding said core member with relatively small clearance therefrom, and a thin film of solder bonding said sleeve to said core member subject to release upon melting of said solder, said core member being of uniform conductivity from terminal to terminal and having surroundings minimizing danger of hot spots therein.

6. A thermal restraining device for electric switches and the like comprising a core member of resistance material having at opposite ends a terminal supporting the same against rotation and having extending from terminal to terminal a thin surrounding covering intimately bonded therewith and comprising an inner layer of insulation and an outer layer of material with which solder will bond, such layers being intimately bonded, a thin film of solder bonded to

said outer layer and a sleeve surrounding said solder film which is locked to said core member by said solder film subject to release upon melting of said film, said core member forming a current conducting path of uniform conductivity from terminal to terminal and having surroundings minimizing danger of hot spots therein in the event of a high current value resulting from short-circuit.

- 10 7. A thermal restraining device for electric switches and other devices, comprising a core member having supporting terminals restraining the same against rotation, said core member comprising high resistance material and having 15 intimately bonded thereto an oxide insulating covering extending from terminal to terminal and a second covering of substantially like extent and of material intimately bonding with said oxide covering and affording a bonding surface for solder, said two coverings having a combined thickness of the order of .002 inch, a film of solder bonded to said second covering and an element rotatable about said core member and having 20 a sleeve bonded to said covered core member 25 through the medium of said solder film subject to release upon melting of said film, said core member affording a current conducting path of uniform conductivity from terminal to terminal and having surroundings minimizing danger of hot spots therein when subjected to current flow 30 of the order of a short-circuit.
